UNITED STATES PATENT OFFICE.

MELVILLE D. JONES, OF BOSTON, MASSACHUSETTS.

DESIGN FOR RECLINING-SETTEES.

Specification forming part of Design No. 5,940, dated June 18, 1872.

Specification describing a Design for Reclining-Settees, invented by MELVILLE D. JONES, of Boston, in the county of Suffolk and State of Massachusetts.

The nature of my design is fully represented in the accompanying drawing, to which reference is made.

The drawing represents one end of the settee, made of iron or other metal, so formed as to represent a vine, which commences with the legs of the settee *a a*, running upward, and intertwining, at *b*, with branches running to the

front *c* and to the back *d*. At *e f g* are leaves. *h i j* is a plate running from the front to the top of the back, to which the bottom and back of the settee is screwed.

What I claim is—

A design for reclining-settees, ornamented substantially in the manner above described, and the general outline.

MELVILLE D. JONES.
